UNITED STATES PATENT OFFICE

161,788

NONREFRIGERATED DEVELOPING TANK

Vernon W. Powell, Decatur, Ill.

Application December 27, 1948, Serial No. 150,397

Term of patent 14 years

(Cl. D61—1)

To all whom it may concern:

Be it known that I, Vernon W. Powell, a citizen of the United States, residing at Decatur, in the county of Macon and State of Illinois, have invented a new, original, and ornamental Design for Nonrefrigerated Developing Tanks, of which the following is a specification, reference being had to the accompanying drawings, forming part thereof.

Fig. 1 is a side elevational view of a nonrefrigerated developing tank, showing my new design,

Fig. 2 is a bottom plan view,

Fig. 3 is a side elevational view taken transversely of Figure 1,

Fig. 4 is a top plan view thereof,

Fig. 5 is a partial sectional view taken on the line 5—5 of Fig. 3.

I claim:

The ornamental design for a nonrefrigerated developing tank, as shown.

VERNON W. POWELL.
